UNITED STATES PATENT OFFICE.

ANDREW JANSEN, OF DALLAS, TEXAS.

APPARATUS FOR BURNING UNBURNED GAS PRODUCTS.

1,132,660.

Specification of Letters Patent. Patented Mar. 23, 1915.

Application filed May 5, 1913. Serial No. 765,463.

To all whom it may concern:

Be it known that I, ANDREW JANSEN, a citizen of the United States, residing at Dallas, in the county of Dallas and State of Texas, have invented certain new and useful Improvements in Apparatus for Burning Unburnt Gas Products, of which the following is a specification.

This invention as specified, relates to new and useful improvements in apparatuses for burning unburnt gas products.

In burning gas such as artificial and natural gas, certain products are not burnt or consumed and these escape, some in the form of fumes technically termed "carbon monoxid" and others in various other forms. These unburnt products are valuable as fuel elements and if burnt would materially add to the combustion and cause the generation of more heat as well as eliminating the fumes. An apparatus burning these unburnt products would consume less gas in generating a given amount of heat than where said products escape and are not combusted.

It is the object of this invention to provide a method for burning all of the products usually known as "waste products" and to eliminate the fumes and poisonous vapors and incidentally to produce an apparatus for carrying out the method. Certain experiments have been made along this line but a complete burning of the waste products has not been effected.

A still further object of the invention is to provide a device of the character described that will be strong, durable, efficient, and simple and comparatively inexpensive to construct, also one in which the several parts will not be likely to get out of working order.

With the above and other objects in view, the invention has relation to certain novel features of construction and operation, an example of which is described in the following specification and illustrated in the accompanying drawing, wherein:

Figure 1 is a front elevation of a heating stove with my invention applied thereto, Fig. 2 is a vertical sectional view on the line $x-x$ of Fig. 1, Fig. 3 is a vertical sectional view on the line A—A of Fig. 2, Fig. 4 is an underside view of the heating stove, and Fig. 5 is a sectional detail of the burner.

In the drawings the numeral 1 design-

nates the front wall of an ordinary stove body, 2 the back wall, 3 the side walls, 4 the top wall, and 5 the bottom wall. Within the stove body or casing a combustion compartment or chamber A is formed which is separated from an air flue B also within the casing. It is necessary that the combustion chamber be entirely closed so that the waste products cannot escape except to the burners as hereinafter described.

The flue B extends entirely across back of the casing in rear of the chamber A. At each side of the chamber vertical side flues C are formed between the side walls 3, the side walls 6 of the chamber and the front wall 7 of the flue. At the top of the chamber a curved deflector plate 8 is disposed transversely and extends over the flues C closing the tops of the same. The deflector plate is highest at the center and curves down toward each flue C. The upper portion of the chamber and the deflector plate form a dome in which the waste products are accumulated.

The bottom 5 of the stove casing has an elongated opening 9 as is already shown in Fig. 4. An ordinary air and gas mixer 10 is inserted in this opening and connected to a gas supply pipe 11 disposed under the stove. A gas pipe 12 leads upward from the mixer into the chamber A, and is connected at its upper end to lateral branch pipes 14. Elbows 15 lead from the lower ends of the flues C as shown in Fig. 3. Burners 16 fit on the upper ends of the elbows and are connected to the branch gas pipes 14.

Each burner 16 as shown in Fig. 5 is annular and has within its wall a vertical annular gas channel 17, the inner wall of which is provided with a plurality of upwardly directed ports 18 disposed radially of the burner. Gas supplied to the channel by the pipe 14 escapes through the ports and is combusted at the center of the burner, the radial disposition of the ports causing the flames to project toward the center of the burner. The lower end of the burner is internally screw threaded and receives a thimble 19 which has its upper portion tapered or contracted while its lower portion which projects below the burner proper, has an internal annular shoulder 20 which rests upon the upper end of the elbow 15, the latter having a snug fit within the thimble.

The burner being lighted and the gas combusted at the burners, certain unburnt products will rise in the chamber A to the dome thereof. As these products accumulate they 5 will flow along the under side of the deflector plate 8 until reaching the side flues C. The unburnt products will pass down the flues C to the elbows 15 and then out through the thimbles 19 which, owing to their con- 10 tracted upper ends direct said products directly into the center of the flame where said products are ignited and combusted. This circulation of the waste products is continuous and completely consumes all combustible 15 elements. It is here pointed out that the waste products must be delivered into the center of the flame in order to be ignited and by so doing an ignition of all the waste products conveyed to the burners is assured. 20 While the invention has been illustrated in connection with a heating stove it is apparent that its field of use is comparatively unlimited. Three elements are necessary to carry out the invention viz: a dome for collecting the waste products, a burner, and means for conveying the collected waste products to the burner.

In some cases a heating flue will be required. This flue is designed to admit fresh 30 air, convey it past the heating chamber and discharge it without bringing said air in contact with the waste products or fumes of the burners. In the drawings the flue B is used for this purpose. The entrance to this 35 flue is through the opening 9. Fresh air enters the flue B through the opening 9 and

passes up said flue, thus being heated. A horizontal flue D is formed at the top of the stove casing over the deflector plate 8. This flue D is formed by the top wall 4, side walls 40 3, and a transverse plate 21 connected with the flue wall 7. In the front wall 1 of the casing an elongated opening 22 is provided in which the flue D terminates and through which heated air is discharged. On the bottom 5 of the stove a pan 23 of water may be placed and moisture supplied to the heated air. 45

What I claim is:

1. A gas burner for burning waste gas 50 products comprising a body having a central opening and provided with gas openings directed toward the central opening, means for supplying gas to the gas openings, and a means for introducing waste gas products 55 into the central opening of the burner body.

2. A gas burner for burning waste gas products comprising a body having a central opening and provided with gas openings communicated with said central opening, 60 means for supplying gas to the gas openings, and means for introducing waste gas products into the central opening of the burner body.

In testimony whereof I have signed my 65 name to this specification in the presence of two subscribing witnesses.

ANDREW JANSEN.
